COMBINATION STABILIZING AND REAMING APPARATUS

De Orr Cook, 88 Eugenia Drive, Ventura, Calif.
Filed Feb. 26, 1960, Ser. No. 11,223

2 Claims. (Cl. 175—295)

This invention generally relates to well drilling operations and tools for use in drill pipe strings, and more particularly concerns a stabilizer or reamer tool designed for interposition in the string to be employed for the function of continuously reaming out the bore hole as well as maintaining the string concentrically positioned within the bore hole.

Apparatus functioning for this purpose, for example, is disclosed in applicant's Patent No. 2,869,827, issued January 20, 1959, entitled "Retrievable Stabilizer for Well Bores."

The combination stabilizing and reaming apparatus of the present invention, however, is also directed to certain additional functions not contemplated by the tool disclosed in the aforementioned patent.

When drilling through certain formations, the particular stabilizer or reamer device as such may become stuck or impacted in the bore hole. Usually, the stabilizer or reamer is at least as large in diameter if not greater in diameter than any of the other components of the drill pipe string. In consequence, although the stabilizer and/or reamer may itself be stuck, the remainder of the string under such circumstances is usually free for rotation, at least above and immediately below the stabilizer.

The most common condition causing freezing of the stabilizer in the well may be attributed to keyseating; for example, when drilling through a soft formation in which the drill pipe (under tension) is operated through a crooked hole. In other instances, upon stoppage of circulation, drill cuttings may accumulate about the stabilizer and effectively freeze it and the coupled string in the hole.

In the past, it has usually been necessary to remove the free portion of the column or string above the particular point at which the pipe is frozen, and thereafter recover the lower portion by fishing operations. In this practice, it is first necessary to ascertain the location of the frozen pipe, and thereafter lower a light charge of "string shot" explosive cord to the top of the critical zone, where it is detonated to deliver a sharp jar to the pipe sufficient to loosen the threaded joint in the nearest collar. The free pipe may then be released by turning it counter-clockwise at the surface and removed from the well. The particular fishing operation may then be commenced to recover the stuck portion of the column.

Another object of the present invention is to provide a stabilizer and reaming apparatus which is so constructed and mounted on the drill pipe string that it may in the event of keyseating or the like co-function with the drill pipe string to jar itself loose instead of requiring the entire free portion of the string above it to be removed and fishing operations employed, as heretofore mentioned.

Another object of the present invention is to provide a relatively simple and economically constructed combination stabilizing and reaming apparatus adapted for interposition in a drill pipe string, which will not only perform its primary function of stabilizing the string and reaming the hole, but which also embodies means such that in co-operation with the string it may be jarred loose in the event of keyseating or otherwise becoming stuck in the hole.

A still further object of the present invention is to provide a combination stabilizing and reaming apparatus for use in a drill pipe string which is rugged in its construction and which has only a single movable part of relatively long life.

2

These and other objects and advantages of the present invention are generally attained by providing in a drill pipe string a stabilizer sleeve slidably mounted thereon for limited axial movement. Co-operative means are provided on the string and the sleeve for coupling the sleeve in a first axial position relative to the string for rotation therewith. In addition, other co-operative means are provided on the string and sleeve for effecting a jarring of the sleeve when it is disposed in a second axial position relative to the string.

In a preferred embodiment, the combination stabilizing and reaming apparatus is made up as a unitary tool for axial inter-position in the drill pipe string and includes an elongated mandrel having an upper end designed to be coupled to an upper part of the drill pipe string and a lower end designed to be coupled to a lower part of the string. The mandrel has an intermediate reduced diameter portion of given axial length to define spaced upper and lower shoulders.

In accordance with a primary feature of the present invention, a stabilizing sleeve is slidably mounted on the reduced diameter portion, with the sleeve being of lesser axial length than the given axial length, and with the sleeve defining a bottom end portion designed to engage the lower shoulder and a top end portion designed for coupling to the upper shoulder. The lower shoulder and the bottom end portion include co-operating means designed upon engagement to effect axial jarring of the sleeve in response to a given direction of rotation of the mandrel relative to the sleeve.

A better understanding of the structure and functions of the combined stabilizing and reaming apparatus of the present invention may be had by reference to the drawings, showing an illustrative embodiment, and in which:

FIGURE 1 is a view of the combined stabilizer and reaming apparatus of the present invention with parts thereof being shown in section, and with the stabilizer sleeve being coupled for normal clockwise rotation with the drill column; and,

FIGURE 2 is a view of the apparatus of FIGURE 1 showing the parts of the combination stabilizer and reamer apparatus in position for jarring of the stabilizer sleeve as such.

Referring now to the drawings there is shown in FIGURE 1 a tubular body or mandrel 10, which preferably comprises a part of the overall tool of the present invention but which could conceivably be a modified portion of the drill pipe string. The mandrel 10 is provided with a passage 11 for communication with the interior of the drill pipe string, and includes at its upper end a threaded joint 12 for connection to an upper part of the drill pipe string (not shown) in a conventional manner.

The mandrel 10 is provided with a reduced diameter portion 13 including threading 14 at the upper end thereof.

The reduced diameter portion 13 has slidably mounted thereon a stabilizer sleeve 15 having external fins or blades 16 similar to those described in the aforementioned Patent No. 2,869,827.

The sleeve 15 is provided with internal threads 17 adapted for coupling to the threads 14 of the reduced diameter portion 13 in the manner as shown in FIGURE 1.

The reduced diameter portion 13 further defines with the body of the mandrel 10 an upper shoulder 18.

The sleeve stabilizer 15 has provided at the lower end thereof ratchet or clutch teeth 19 designed in one relative positioning of the sleeve 15 and mandrel 10 to engage a collar or lower end portion 20 of the mandrel 10. The collar 20, towards this objective, includes mating teeth 21 designed to co-operate with the clutch teeth 19 in a manner that will become clearer as the specification

proceeds. The collar 20 is preferably a separate member expanded by heating and shrunk on to the mandrel 10.

The mandrel 10 terminates at its lower end in a threaded joint 22 designed for coupling to a joint 23 of a lower part of the drill string 24, as more clearly shown in the view of FIGURE 2. Of course the lower portion of the drill string 24 also includes an inner passage 25 designed for communication with the passage 11 and the passage of the upper part of the drill string (not shown) in a conventional manner for the circulation of drilling mud.

The operation of the combined stabilizing and reaming apparatus of the present invention may now be described. In normal drilling practice, the apparatus will be axially interposed in the drilling column in the manner as shown in FIGURE 1 with the joint 12 threaded to an upper part of the drill string and the joint 22 threaded to a lower part 24 of the drill string. As, in conventional practice, the drill string or column will be rotated clockwise (looking down) as indicated by the arrow adjacent 20 the sleeve 15. In the event that the stabilizer 13 becomes stuck because of keyseating or other freezing thereof with respect to the side walls of the bore hole, the present apparatus enables freeing of the sleeve 15 without removal of the drilling column or string.

Towards this end, as in conventional practice, a "string shot" is lowered to a point adjacent the threaded connection 22-23 with the explosive being detonated to loosen this joint preparatory to unthreading. Thereafter, the drill pipe column is rotated counter-clockwise to effect an unthreading of the joint 22-23. It will be appreciated that as the joint 22-23 is being unthreaded, the upper thread 17 of the sleeve 15 will also be unthreaded from the threads 14 on the reduced diameter portion 13. Toward this end, the threads 14 and 22 are both right hand threads; also, preferably the threads 14 are straight threads while the threads 22 are tapered threads such that the threaded joint 22-23 will be uncoupled sooner than the joint made up of threads 14-17. It is conceivable that if this design were different, that it would be possible for relative axial movement to occur between the sleeve 15 and the mandrel 10 to effect engagement of the teeth 19 and 21 prior to the time that the joint 22-23 were loosened; in such event, further counter-clockwise rotation of the mandrel 10 could not be effected.

After the joints 22-23 and 14-17 have been uncoupled, the drilling column is lifted upwardly in the direction of the arrow into the position as shown in FIGURE 2. Thus, the reduced diameter portion 13 will move axially upward relatively to the now stuck sleeve 15 since the sleeve 15 has a slightly larger internal diameter than the reduced diameter portion 13.

Thereafter, the drilling string may again be rotated in a conventional clockwise direction, while still maintaining the column or string under tension.

As this latter rotation occurs, the teeth 21 will be forced axially downwardly relative to the teeth 19 through 180° rotation because of the inclined mating surfaces, and thereafter jarred upwardly relative to the teeth 19 to cause a sudden impact on the lower end of the sleeve 15. A further 180° rotation will again effect a gradual lowering of the teeth 21 to be terminated again by a sudden upward movement thereof, to again jar the sleeve 15.

It will be appreciated after several revolutions of the drill pipe column and the resultant jarring occurring between the teeth 19 of the sleeve 15 and the teeth 21, that the stabilizer sleeve 15 will become free of the surrounding side walls so that the drilling operation may again be commenced.

At such time, the drill pipe column is again lowered such that the threads are again coupled to the threads 23, and that the threads 14 of the reduced diameter portion 13 are again coupled to the upper threads 17 of the stabilizer sleeve 15, by clockwise rotation of the drill pipe string.

Preferably, prior to making up the threaded connection between the sleeve and mandrel, the sleeve is pulled up the hole a short distance to assure that the threading connection between threads 14 and 17 will be made up initially and prior to the joint 22-23.

In the event that certain of the drill collars are also frozen in the well hole, the tool after being made up, may be used as a reamer for drilling up through the hole to condition it so that fishing tools may safely be run in to regain the drill collars left in the hole. Of course, if no drill collars were stuck, drilling may be commenced without any further work stoppage.

It will be apparent from the foregoing that the combined stabilizing and reaming apparatus of the present invention not only functions for its primary purpose, but also enables a rugged and simple method of expeditiously loosening the stabilizer in the event it becomes stuck or frozen in the side walls of the bore hole without the necessity of removing the drill column. In addition, the apparatus of the present invention is made up of only two parts, the sleeve and the mandrel, it being possible as heretofore mentioned to embody the mandrel as a section of the drill pipe string by modifying it as indicated.

Certain modifications and changes in the structure of the combined stabilizing and reaming apparatus of the present invention will occur to those skilled in the art. Such modifications and changes are deemed to fall within the scope of the present invention as set forth in the following claims.

What is claimed is:

1. A stabilizing and reaming apparatus comprising, in combination: a mandrel having a threaded portion adjacent to its upper end and a jarring means adjacent to its lower end spaced a given axial distance below said threaded portion; a stabilizing sleeve of axial length less than said given axial distance freely rotatable and slidable along said mandrel between said threaded portion and said jarring means, said sleeve having threads at its upper end for threaded connection to said threaded portion when in a first position and cooperating jarring means at its lower end for engagement with said jarring means adjacent to the lower end of said mandrel when axially moved to a second position, whereby said mandrel may form part of a drill pipe string and said sleeve held against axial movement and rotated with said drill pipe string in a first direction when in said first position in threaded engagement with said threaded portion, and whereby said drill pipe string may be rotated in an opposite direction and raised to reposition said sleeve in said second position to effect a jarring of said drill pipe string.

2. An apparatus according to claim 1, in which said jarring means and cooperating jarring means comprise ratchet teeth on said lower end of said mandrel and sleeve, respectively.
